DESIGN FOR A VISIBLE CARD INDEX CABINET

Carl F. Wolters, Buffalo, N. Y.

Application February 20, 1934, Serial No. 50,785

Term of patent 14 years

To all whom it may concern:

Be it known that I, CARL F. WOLTERS, a citizen of the United States, residing at Buffalo, in the county of Erie and State of New York, have invented a new, original, and ornamental Design for a Visible Card Index Cabinet, of which the following is a specification, reference being had to the accompanying drawing forming part thereof.

Fig. 1 shows my new design of visible card index

cabinet in perspective with the covers for the top in closed position.

Fig. 2 shows my new design of visible card index cabinet in perspective similar to Fig. 1 with the covers in open position.

I claim:

The ornamental design for a visible card index cabinet, as shown and described.

CARL F. WOLTERS.
